UNITED STATES PATENT OFFICE.

SHELBY N. GRIFFITH, OF DOYLESTOWN, PENNSYLVANIA.

ELECTRICAL-FIXTURE UNIT.

Application filed August 21, 1923. Serial No. 658,619.

This invention relates to electrical fixture units and, more particularly, to a unit which will provide an auxiliary current outlet or current tap.

It is the primary object of this invention to provide a unit which may be interposed anywhere in the line of support of an ordinary electrical lighting fixture, and which will supply an additional current tap on outlets, thereby making it unnecessary to make the connection at the socket of the fixture.

In the modern household many portable electrical devices are used, such as fans, 15 toasters, heaters, flat irons, percolators, curling irons, etc., and it is common practice when such are to be used, to remove a lamp bulb from the ordinary lighting fixture and operate the device therefrom. To do this is 20 often a great inconvenience, as it may be desirable to use the lamp at the same time. Likewise wall receptacles are sometimes provided for the exclusive operation of such electrical devices, but in addition to being 25 expensive to install and unsightly, are often located at a point remote from where the lighting fixtures are installed, and, should illumination be necessary, cannot be used unless an extra long connection cord is 30 provided.

It is therefore an object to provide an electrical fixture unit which will provide a quick and handy method for tapping such electrical devices, or utilized for any other 35 purpose found desirable, and so incorporated with the lighting fixture that there will be no indication of such an auxiliary current outlet when not in use.

Other objects and advantages will be apparent in the following detailed description taken in connection with the accompanying drawings, forming a part of the specification, in which drawings:

Figure 1 is a side elevation of an electrical fixture constructed according to my invention, having one of the units thereof equipped with an auxiliary current outlet.

Figure 2 is an enlarged plan view of the unit shown in Figure 1 with the cover removed.

Figure 3 is a vertical sectional view of

the unit taken on the line 3-3 of Figure 2, and,

Figure 4 is a vertical sectional view of the unit, taken on the line 4-4 of Figure 2. 55

In the drawings, wherein for the purpose of illustration is shown the preferred embodiment of my invention, the letter A designates an electric light fixture; B a unit or receptacle housing interposed in the line of support of said fixture; and C, a current tap receptacle enclosed in the unit B.

The electric light fixture A may be of any approved style or design and as illustrated in the drawings consists of a canopy 65 10, a stem 11, to which is connected the unit B, and has extending therefrom the conventional lamp socket 12. Through this fixture A, extends the main circuit wires 13 and 14 which will be more fully described 70 hereinafter.

Referring now to the unit or receptacle housing B which may be positioned anywhere in the line of support of said fixture, as shown such includes a spherical shell 15 and a cover 16. Extending radially from the shell 15 are a pair of externally screw threaded nipples, an inlet nipple 17 for connection to the stem 11 and through which the wires 13 and 14 enter, and an outlet 80 nipple 18 for connection to the lamp socket 12 and for the purpose of leading the main circuit wires into said socket. Upon the upper marginal edge 19 of the shell 15 are formed inwardly extending diametrically 85 disposed retaining lips 20 and 21 and for a purpose to be subsequently set forth. Suitable means, such as an annular raised ring 22, may be carried interiorly of the shell 15 for keeping the receptacle C in a 90 correct position. The cover 16 is preferably formed so as to conform to the configuration of the shell 15 and may be hingedly connected thereto as at 23 and provided with a cover clasp 24 for retaining it in a closed 95 position when not in use.

Concerning the current tap receptacle C, which may be made of any shape and size to accommodate various styles of units, as shown includes a cylindrical shaped insulating base 25, and may have an annular 100 groove 26 at one end thereof for accommo-

dating the annular raised ring 22 of the shell 16 in order that the receptacle C may be held in a correct position. It is obvious that other means may be employed for accomplishing this purpose and such is merely by way of illustration. Ways 27 and 28 extend through the receptacle base 25 for the purpose of leading the wires 13 and 14 respectively to and from the contact points 10 which will now be described. These contact points 29 and 30 are insulated from each other and are constructed so as to accommodate a push type plug, such as is now in common use. Lips 31 may extend from 15 the outer member of the contact points 29 and 31 upon which bared portions of the wires 13 and 14 are adapted to rest and be held in intimate contact with the contact points by suitable devices, such as binding 20 screws 32. Recesses 33 are provided in the base 25 in order that the wires 13 and 14 may be connected to the contacts 29 and 30, and such may be filled in or covered if desired, after the connections are made. An 25 annular groove 34 is formed around the upper marginal edge of the receptacle base 25 and forms a seat for a retaining ring 35 positioned thereon. This ring 35 also has an annular groove formed around its upper 30 marginal edge defining an outer ring 36, said outer ring 36 provided with radially extending slots or recesses 37 open to the outer edge. When it is desired to clamp the receptacle base 25 securely in the shell 15, the ring 35 is placed thereon so that the slots 35 37 register with the retaining lips 20 and 21. This will allow the ring 35 to seat in the annular groove 34, and by rotating the ring 35, the outer ring 36 will move under the lips 20 and 21 and hold the receptacle base 10 in place.

When it is desired to equip an electric lighting fixture with a unit and receptacle such as has been described, the unit or receptacle housing B is placed in the line of support and the wires 13 and 14 enter the housing B through the inlet nipple 17. The receptacle C has not yet been placed in the housing B, and the wires 13 and 14 are passed through the ways 27 and 28 respectively. A portion of the wires 13 and 14 lying nearest the contact points 29 and 30 is stripped of its insulation, the bared wires placed upon the lips 31 and securely clamped to the contact points by means of the binding screws 32. The wires are then led out of the housing through the outlet nipple, and receptacle C is then placed in the shell 15 so that the groove 26 seats upon the raised ring 22. The ring 35 is then placed upon the receptacle base 25 and by circumferential movement imparted thereto will lock the receptacle C in place and prevent a person from pulling the receptacle C out of the housing when disconnecting a temporary 60 65 85

electrical device from the unit. Should it be necessary at any time to remove the receptacle C from the housing B such may be accomplished by removing the retaining ring 35, as there is always considerable free or slack wire to permit of its removal. 70

While I have herein described and in the drawings illustrated the invention applied as a receptacle housing disposed at the outer end of a wall bracket, such is merely by way of example and it is to be understood that the unit may be interposed anywhere in the line of support of an electric lighting fixture and may be made of various sizes and shapes to conform to the lines and workmanship of 80 the fixture.

Various changes in the shape, size and arrangement of parts may be made to the form of invention herein shown and described, without departing from the spirit of the invention or the scope of the claims. 85

I claim:

1. In combination with an electric lighting fixture of the wall bracket type embodying a rigidly mounted stem, a socket, and a 90 housing rigidly connecting the stem and socket, a receptacle mounted in said housing including a base having independent ways formed therein for the leading of main circuit wires therethru from the stem to said socket and having recesses opening at the outer surface of the base and communicating with said ways intermediate the ends thereof, contacts carried by said base and projecting into said ways at their intersection with said outwardly opening recesses, and binding screws, carried by said contacts at said recesses for clamping bared portions of said line wires in electrical contact one with each of said contacts. 95 100 105

2. In combination with an electric lighting fixture embodying a rigidly mounted stem and a socket, a receptacle housing having inlet and outlet nipples for connection respectively to the stem and socket and forming a part of the line of support for the socket, a receptacle mounted in said housing including a base having independent conduit ways formed therethru and opening at opposite ends adjacent the inlet and outlet nipples, independent contacts carried by said base and projecting one into each of said conduit ways intermediate the ends thereof, and means for clamping line wires to said contacts intermediate the end of said ways. 110 115 120

3. An electric lighting fixture of the wall bracket type comprising a hollow supporting stem, a housing having a reduced screw threaded nipple for threaded connection with the outer end of said stem, and a reduced screw threaded nipple depending from the underside of the housing, a lamp socket in threaded connection with the nipple at the lower end of the housing, a receptacle mounted in said housing including a base 125 130

having conduit ways extending therethru with their opposite ends opening adjacent said angularly disposed nipples, said base also having recesses extending into said ways intermediate the ends thereof, said conduit ways adapted to permit of line wires from the stem to be trained unbroken thru the base to said lamp socket, independent con-

tacts carried by the base and opening at the upper face thereof and having their lower ends projecting into said conduit ways at said recesses, and binding screws in threaded engagement with said contacts at the recesses for clamping portions of the line wires to the contacts. 10
